UNITED STATES PATENT OFFICE.

DAVID K. ALLINGTON, OF EAST SAGINAW, MICHIGAN.

WATER-HEATER.

SPECIFICATION forming part of Letters Patent No. 234,645, dated November 23, 1880.

Application filed June 18, 1880. (No model.)

To all whom it may concern:

Be it known that I, DAVID K. ALLINGTON, a citizen of the United States, residing at East Saginaw, in the county of Saginaw and State 5 of Michigan, have invented a new and useful Water-Heater, of which the following is a specification.

The object of my invention is to construct a water-heater in such a manner that the 10 condensed steam or drip-water and vapor that escapes from a steam salt-works or other steam evaporating-works, and from leaks in the pipes, is salted or mixed with any foreign matter, so that it is unfit to return to the steam-boilers 15 and is run to waste; that the heat that it contains may be utilized either by heating the water that is used to feed the steam-boilers or in heating the brine or other fluid that runs to and is used in the salt or other evaporating-works, and so that all, or nearly all, the 20 heat that is in the drip may be taken up or transferred to the feed-water to the boilers, or the brine or other fluid, as it is run to the works.

25 In the drawings, Figure 1 is a plan view, and Fig. 2 a cross-section.

Like letters denote corresponding parts in all of the figures.

The pipe *b*, Figs. 1 and 2, is provided at its 30 opposite ends with the heads and stuffing-boxes *e* and *e*, and the inlet-pipe *a* and outlet-pipe *c*.

The pipe *d*, Figs. 1 and 2, is placed inside of the pipe *b* and runs its whole length, as is shown by the pipe *b* being cut away at *d d d*, and passes out through the stuffing-boxes *e* and *e*, Fig. 1, the stuffing-boxes allowing the pipe *d* to slip, so as to relieve the pipes *b* and *d* from any strain that might be caused from unequal expansion.

40 The pipes *b* and *d*, Figs. 1 and 2, may be placed in a coil, or in a straight line, or any other form that will be most convenient for the purposes herein described, and in place of the pipe *d* there may be any desired number of pipes running through the pipe *b*, so that cold water or other fluid may be introduced at one end, and hot drip and vapor at the opposite end.

When the heater is used to heat the feed-water for steam-boilers, the cold water enters 50 the pipe *b* through the inlet-pipe *a*, and runs

its whole length and discharges through the outlet-pipe *c* at the opposite end, from which it may be conducted to the steam-boilers of an evaporating-works; or, when used to heat 55 the brine or other fluid to be evaporated in the evaporating-works, it can be conducted from the discharge-pipe to any part of the evaporating-works that may be desired.

The hot drip-water and vapor from the drip-pipe of a steam evaporating-works is conducted to and enters the pipe *d* at *f*, Fig. 1, and runs its whole length, and is discharged and run to waste at *g* at the opposite end. By this means the cold water or brine, or other 65 fluid, enters the heater at one end, and the hot drip-water and vapor from the evaporating-works at the opposite end, and they run in opposite directions, so that all, or nearly all, of the heat that is contained in the drip-water 70 and vapor may be transferred to the feed-water to the steam-boilers, or to the brine or other fluid that is to be evaporated in the evaporating-works.

The hot drip-water and vapor that enters 75 the pipe *d* at *f* will discharge at *g* as cold, or nearly as cold, as the water or other fluid that enters the pipe *b* through the inlet-pipe *a*, and the cold water or other fluid that enters the pipe *b* through the inlet-pipe *a* will, when 80 discharged through the discharge-pipe *c*, be nearly or quite as hot as the drip-water and vapor that enters the pipe *d* at *f*, thereby utilizing all or nearly all of the heat that is contained in the drip-water by transferring it 85 to the feed-water for the steam-boilers, or to the brine or other fluid that is to be evaporated in the steam evaporating-works.

The cold brine or other fluid to be used in the evaporating-works, or the feed-water for 90 steam-boilers, may be run through the pipe *d*, and the hot drip-water and vapor run through the pipe *b*, they being introduced at opposite ends and run in opposite directions, so that all of the heat contained in the drip-water and 95 vapor that is run through the pipe *b* may be transferred to any fluid that is run through the pipe *d*.

When the heater is laid in coil, instead of using the heads and stuffing-boxes *e e*, I may 100 use plain heads, the inside pipe, *d*, being threaded with a long thread to screw through

the head and receive a coupling on the outside, from which the pipe may be continued to any desired point, the difference in the size of the pipes *b* and *d* being sufficient to relieve all strain from unequal expansion.

5 What I claim as my invention is—

The water-heater herein described, consisting of the outer pipe, *b*, provided with the heads and stuffing-boxes *e*, the inlet-pipe *a*,

and discharge-pipe *c*, in combination with the inner pipe, *d*, all constructed and arranged as shown and described, and for the purpose described.

DAVID K. ALLINGTON.
